UNITED STATES PATENT OFFICE.

ERNEST C. HUFFORD AND WELLS S. BATES, OF WATTS, CALIFORNIA.

DESIGN FOR A TIRE-TREAD.

56,616.

Specification for Design.

Patented Nov. 16, 1920.

Application filed April 20, 1920. Serial No. 375,400. Term of patent 7 years.

To all whom it may concern:

Be it known that we, ERNEST C. HUFFORD and WELLS S. BATES, citizens of the United States, residing at Watts, in the county of Los Angeles and State of California, have invented a new, original, and ornamental Design for Tire-Treads, of which the following is a specification, reference being had to the accompanying drawing, forming a part thereof.

Figure 1 is a plan view of a section of the tire tread, and

Fig. 2 is a cross section thereof.

We claim:

The ornamental design for a tire tread as shown.

ERNEST C. HUFFORD.
WELLS S. BATES.
